(57) CLAIM

The ornamental design for a chaise, as shown and described.

DESCRIPTION

FIG. 1 is a top, front, right perspective view of a chaise showing our new design;

FIG. 2 is a front view thereof;

FIG. 3 is a rear view thereof; and,

FIG. 4 is a right side view thereof.

The uneven length broken lines immediately adjacent to the shaded area represent boundary lines and form no part of the claim. The even length broken lines represent the portions of the chaise that form no part of the claimed design.
